Atty.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,833, dated March 21, 1882.

Application filed February 11, 1882. Term of patent 3½ years.

To all whom it may concern:

Be it known that I, HENRY HUNT, of Greenville, in the county of Hudson and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The leaf-like figure A springs from the blank field B, and, opening upward, partly traverses the blank field C. A similar leaf-like figure, D, springs from the same blank field, B, and, opening downward, partly traverses the blank field E. To the right of the blank field B is a blank field, F, from which spring two leaf-like figures similar to A, one opening toward the right and the other, G, toward the left, G partially traversing the field B and concealing the origin of D. To the left of B is another blank field, from which spring similar leaf-like figures, opening, 25 L toward the right and the other toward the

left, L partially traversing the field B and concealing the origin of A. From the blank field C spring two similar leaf-like figures, N O, opening, N toward the right and O toward the left, and the field C is partly traversed by the leaves A from below and P from above, concealing the origin of O and N. Thus it will be seen that the field B gives origin to two leaf figures that traverse respectively the two adjacent blank fields above and below, while B 35 itself is traversed by two leaf figures that find their origin, respectively, in the two adjacent blank fields to the right hand and to the left, and that this is true of the alternate fields, both horizontally and vertically, on the design, and 40 is true of the other fields with the directions changed a quarter of a circle.

I claim—

The design for carpets, consisting of the grounds and figures A, B, C, D, E, F, G, K, L, 45 N, O, and P, substantially as shown.

HENRY HUNT.
